UNITED STATES PATENT OFFICE.

JAMES M. CONNER, OF GREENVILLE, NEW JERSEY.

DESIGN FOR PRINTING-TYPES.

Specification forming part of Design No. 7,253, dated March 24, 1874; application filed November 18, 1873.
[Term of Patent 7 years.]

A.

To all whom it may concern:

Be it known that I, JAMES M. CONNER, of Greenville, Hudson county, New Jersey, have originated and produced a new and original Design for Printing-Type, of which the following is a specification:

The nature of my design is fully shown in the accompanying typographic impression, to which reference is made.

What I claim as new is—
The design for printing-type, as shown.

JAMES M. CONNER.

In presence of—
GEORGE JEFFERYS,
Wm. C. CONNER, Jr.,
JOSEPH H. TOONE.
